United States Patent Office

Des. 222,751
Patented Dec. 21, 1971

222,751

COUPLER

Melvin Rudin, Palo Alto, Calif., assignor to Datel Corporation, McLean, Va.

Filed Nov. 4, 1970, Ser. No. 25,828

Term of patent 14 years

Int. Cl. D14—03

U.S. Cl. D26—14

FIG. 1 is a perspective view showing my new design;
FIG. 2 is a top plan view thereof;
FIG. 3 is an end view thereof;
FIG. 4 is one elevational side view thereof;
FIG. 5 is a view of the opposite end thereof; and
FIG. 6 is an elevational view of the opposite side
thereof.

I claim:

The ornamental design for a coupler, as shown.
